UNITED STATES PATENT OFFICE.

SAMUEL B. WILLIAMS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed April 21, 1924. Serial No. 707,795.

To all whom it may concern:

Be it known that I, SAMUEL B. WILLIAMS, a citizen of the United States of America, residing at Brooklyn, in the county of Kings, 5 State of New York, have invented certain new and useful Improvements in Telephone Systems, of which the following is a full, clear, concise, and exact description.

This invention relates to telephone systems, 10 and particularly to systems of the character in which automatic switching equipment is employed for the establishment of connections.

In systems employing machine switches 15 of the coordinate type in which link circuits are involved and consequently a comparatively large number of contacts, it is desirable to make a test to ascertain the condition of these contacts whenever a connection is 20 established to a subscriber's line. If the switch is operating properly and all of the contacts are closed, then the operation may be proceeded with and ringing current applied to the subscriber's line. However, if 25 certain of the switch contacts fail to close properly and this abnormal condition is detected, the ringing current may be withheld from the subscriber's line and a signal given to an operator or an attendant.

It is, therefore, the object of this invention 30 to perform a test of the talking circuit established through the switches of ascertain whether or not said circuit is in proper condition.

A feature of the invention consists in 35 establishing a test path which includes the talking circuit extended through the contacts of the switches to the subscriber's line, without including said line, for the purpose of determining the continuity of said talking circuit.

A further feature relates to the provision, 40 in a system having switches and switch controlling markers of a test circuit comprising the trunk leading to the switches and the contacts of said switches, said test circuit also including the source of talking battery in the trunk and responsive means in the associated marker.

Another feature consists in the provision 45 of a signal associated with the switch controlling apparatus and which becomes effective in case the test reveals an unstandard condition together with means for preventing further progress of the connection.

Referring to the drawing, Figs. 1 to 10, inclusive, when taken in the order illustrated in Fig. 11 disclose a portion of a telephone system embodying the features of this invention.

Fig. 1. shows an interoffice trunk incoming from a distant office together with certain controlling apparatus associated therewith.

Fig. 2. shows an incoming selector switch in which incoming trunks terminate.

Fig. 3. shows a portion of one of the final or connector switches in which the called subscriber's lines terminate.

Fig. 4 illustrates diagrammatically a sender selector switch and also a portion of one of the common register senders.

Fig. 5. shows a sender connector for connecting the register senders to the markers.

Figs. 6 and 7 illustrate one of the common markers, the function of which is to control the incoming and final switches.

Fig. 8 shows an incoming frame connector for connecting the markers to the frames of the incoming selectors.

Fig. 9 shows a translator connector for the purpose of connecting any of the markers to any of the final translators.

Fig. 10 shows one of the final translators, the function of which is to cooperate with the marker to control the final switches.

General description of the circuits and apparatus.

The trunks which lead from distant offices to the office illustrated in the drawing terminate in vertical rows of contacts of incoming selector switches such as the switch 200. The trunk 100 illustrated, for example, appears in the vertical row 201 of the switch 200. Other similar trunks also occupy the same and other vertical rows of this switch. The incoming trunks also appear in vertical rows of contacts of the sender selector switches 400.

For convenience in the method of controlling the switches, the incoming selectors 200 are divided into a number of groups. The trunks which appear in the incoming selectors of a given group are segregated in one or more vertical rows of contacts on the sender selector switches 400. By this means whenever a vertical magnet controlling a given row of contacts on the sender selector 400 is operated, it records an indication in the sender, identifying the par-

ticular group of incoming selector switches to which extends the trunk involved in the connection.

The incoming selectors 200 have access to 5 groups of trunks which appear in vertical rows such as the row 204, which trunks lead to final or connector switches 300, which in turn, have access to the called subscribers' lines. One of these trunks 213 is shown in 10 full, appearing in the vertical row of contacts 301 of the connector switch 300. A number of called subscribers' lines are also 15 illustrated appearing in vertical rows of contacts 303 and 304.

15 The incoming and final switches 200 and 300 and the sender selector switches 400 are 20 of the coordinate type such as generally shown and described in the copending application of J. N. Reynolds, Serial No. 486, 25 367, filed July 21, 1921, Patent No. 1,507,140 issued September 2, 1924 and in the patent to 30 Samuel B. Williams No. 1,517,331, issued December 2, 1924. The operation of the 35 switches and controlling apparatus illustrated in this case is similar to that described more in detail in my copending application Serial No. 701,006, filed March 22, 1924.

The subscribers' lines considered as called 40 lines are divided into a suitable number of 45 groups. If it be assumed that the exchange comprises 10,000 lines, it may be convenient to divide these into twenty groups of 500 lines each. For each group of 500 lines a suitable number of connector switches 300 50 are provided for making connection therewith. Furthermore, each group of 500 lines is provided with a final translator 1000 which is common to all of the connector 55 switches of the group and serves to selectively operate the same. The translator 1000 is made up of three multicontact relays 1008, 1012 and 1013. The first two of these relays each have contacts representing 200 60 different subscribers' lines, and the third relay 1013 has contacts representing 100 subscribers' lines. The grid wires with which these relays make contact are divided 65 into four different sections, and four relays 1014, 1015, 1016 and 1017 each corresponding to a section are also provided. These 70 relays are controlled from the hundreds and units registers 601 and 603 of the marker in accordance with whether or not the hundreds and units digits are less than 5 or 75 greater than 4. For example, if the hundreds digit is greater than 4 and the units digit is less than 5, the relay 1014 is operated, whereas if both hundreds and units digits are greater than 4 the relay 1015 is 80 operated.

By selecting one of the relays 1008, 1012 or 1013 in accordance with the setting of the hundreds register 601 and by selecting one of the relays 1014 to 1017 in accordance with 85 the combined setting of the hundreds regis-

ter 601 and the units register 603, a selecting circuit depending upon the setting of the tens register 602 is extended through the translator to choose the proper vertical operating magnet on the connector switch which has access to the group of subscribers' 90 lines containing the wanted line.

Connector switches 30 comprise five sets of horizontal links 311, 312, etc. The subscribers' lines appear in the vertical rows of 75 contacts 303, 304, etc., each line appearing before all of the horizontal links in the section. Thus, the vertical row of contacts 303 includes five different lines, each having a 80 different one of the ten unit digits.

When the incoming trunk has been extended through the sender selector switch 400 to an idle register sender, the impulse receiving relays 402, 403 and 404 are included in series with the trunk and respond to codes of impulses transmitted thereover in accordance with the desired designation. These relays control a set of registers, not shown, upon which the different digits of the desired number are recorded. After the recording of a designation, the sender is associated with the marker by means of the sender connector 500 and the number recorded on the sender registers is transferred to the corresponding registers 600, 601, 602 and 603 of the marker. For an understanding of the manner in which the sender responds to code impulses transmitted over the incoming trunk, reference is made to the 90 patent to S. B. Williams and E. S. Gibson, No. 1,543,967, granted June 30, 1925.

While the present invention has been embodied in a system involving interoffice trunking, it will be understood that it is also applicable to local switching equipment and that the trunks which terminate in the incoming selectors 200 may be trunks incoming from switches in the local office.

Referring again to the markers, these mechanisms are arranged to be connected to the incoming selector switches 200 by means of the frame connectors 800. Each frame connector 800 serves to connect any of the markers to any of the incoming switches 200 in a given group.

Detailed description of the operation

It will be assumed that a connection which has been extended over the interoffice trunk 100 is desired to be completed to the called subscriber's line 319. When the trunk circuit is closed at the distant office a circuit is completed for operating the relay 103, traceable from battery through the left winding of said relay, left contact of relay 102, upper left winding of repeating coil 106, upper outer back contact of relay 101, thence over the trunk circuit 100 and returning through the lower outer back contact of relay 101, lower left winding of coil 120 125 130

106, contact of relay 102, through the right winding of relay 103 to ground. Relay 103 operates the relay 401 in a circuit from ground through the left contact of relay 5 103, inner upper contact of relay 101, inner upper contact of relay 108, winding of relay 401 to battery. Relay 401 initiates the operation of the sender selector switch 400 which functions to extend the trunk 100 10 to an idle register sender. During the operation of the sender selector 400 ground potential is placed on the conductor 415 which leads through the inner back contact of relay 411, winding of the selector holding relay 410 to battery. Relay 410 operates 15 and locks through the contact of relay 406 to ground. Relay 410 operates the relay 411. Relay 411 operates the relay 101 in the following circuit: Battery, through the 20 winding of relay 101, conductor 114, through the switch 400, conductor 415, inner front contact of relay 411, winding of relay 412, to ground at the outer contact of relay 411. Relay 101 releases the relay 401. Relay 25 101 operates the slow-to-release relay 104, and opens the circuit of relay 103, permitting this latter relay to release.

The apparatus is now ready to receive code impulses and relays 402, 403 and 404 30 respond to these impulses to set up the record on the registers of the sender. After the record has been recorded relay 417 operates and initiates the operation of the sender connector 500 by causing the operation of relay 501. The circuit for this purpose 35 may be traced from ground through the contact of relay 417, back contact of relay 407, back contact of relay 408, contact of relay 409, conductor 418, lower winding of relay 40 501 to battery at the contact of relay 502. Relay 501 locks in a circuit from battery through the winding of relay 502, upper contact and winding of relay 501 to ground over conductor 418. Relay 502 also operates 45 in this circuit and prevents subsequent operation of another relay similar to relay 501, in case a second sender attempts connection to the marker. Relay 503 now operates in a circuit from battery through its 50 winding, lower contact of relay 501, outer contact of relay 504 to ground at the inner right contact of relay 502. Relay 503 locks through its own contact to ground at the left contact of relay 502. Relay 502 operates 55 relay 506 which relates to the first idle marker (it being assumed that the marker represented by relay 509 is busy at the time.) The circuit for relay 506 may be traced from ground through the inner right contact of relay 502, inner back contact of relay 504, lower front contact of relay 510, lower back contact of relay 509, lower back contact of relay 505, lower winding of relay 506 to battery at the upper contact of relay 508. Relay 506 locks in a circuit from battery 60 through the winding of relay 508, upper winding and contact of relay 506 to ground at the contact of relay 502. Relay 508 also operates in this circuit. Relay 506 operates relay 504 in a circuit from battery through the winding of the latter of relay, upper contact of relay 506 to ground at the contact of relay 508. The multicontact relay 507 is next operated to extend the various leads from the sender to the selected idle marker. The circuit for relay 507 may be traced from battery through the winding thereof, middle upper contact of relay 506 to ground at the inner contact of relay 508. Relay 505 also operates in parallel with relay 507. 75

As soon as the sender is connected to the marker the holding relay 700 is operated in a circuit from battery through the winding thereof, conductor 701, thence through the sender connector 500 to ground in the associated sender. Relay 700 locks in a circuit through its winding and contact right back contact of relay 703 to ground at the inner left contact of relay 704. 80

The record of the thousands, hundreds, tens and units digits and also a record of the particular group of incoming switches involved are now transferred from the sender to the marker. First considering the record of the group of incoming selectors to which the trunk 100 extends, it will be noted that this trunk appears in the vertical row of contacts in the sender selector switch 400 which is controlled by the vertical magnet 420. At the time magnet 420 operated in 90 extending the trunk to the sender, it closed an obvious circuit for relay 421 in the sender. Relay 421 operates and locks in any desired manner. Thereafter when the sender is associated with the marker the relay 421 causes the operation of the relay 606 in the marker by means of a circuit traceable from ground through the right front contact of relay 421, conductor 422, through the connector 500, winding of relay 606 to battery. Relay 606 95 operates and selects the frame connector 800 as the one to be operated for connecting the marker to the proper incoming switch 200 in the proper group of incoming switches. 100

It may be assumed that the numerical record set up in the sender shown in Fig. 4 is one which when transferred to the registers of the marker illustrated in Fig. 6 causes the operation of the following relays: relay 610 of the thousands register 600, relay 613 of the hundreds register 601, relays 616 and 617 of the tens register 602 and relay 620 of the units register 603. 110

As is described in copending application Serial No. 703,362, filed April 1, 1924, all of the remaining relays of the marker which do not correspond to operated register relays in the sender are energized momentarily. As soon as all of these relays have been 120 energized a series circuit is completed from 125

130

ground through the left contact of relay 623, thence through similar contacts of all preceding register relays, through the winding of relay 640 to battery. Relay 640 operates and locks through its winding and lower front contact, normal contact of relay 641, conductor 624, conductor 512, right contact of relay 705, outer right contact of relay 710, right back contact of relay 711, conductor 716, inner right contact of relay 712, conductor 713 to ground at the middle right contact of relay 700. Relay 640 operates the relay 641 which locks through its lower contact to the grounded conductor 624. Upon the operation of relays 640 and 641, all of the momentarily operated register relays of the marker are released and only these relays which represent the designation remain energized. Relay 640 thereupon releases. The relay 625 is now operated to subsequently determine the selection of a connector 900 for connecting the marker to the proper one of the twenty different final selectors. The circuit for this relay may be traced from battery through the winding thereof, inner right back contact of relay 615, conductor 626, conductor 627, upper front contact of relay 641 to the grounded conductor 624. With relay 606 operated a circuit is closed for operating the frame connector start relay 804 which is individual to the marker illustrated. This circuit may be traced from battery through the winding of relay 804, conductor 807, right back contact of relay 605, right front contact of relay 606 to ground on conductor 626. Relay 804 operates the relay 805 in a circuit traceable from battery through the lower winding of relay 805, front contact of relay 804, back contacts of relays similar to relay 804, left back contact of relay 802 to ground at the armature of relay 803. Relay 805 operates the slow release relay 803 in a circuit from battery through the winding of the latter relay, right contact of relay 802, lower contact of relay 805, conductor 809, outer right contact of relay 712, to the grounded conductor 713. Relay 805 being slightly slow to release, does not retract its armatures while relay 803 is operating. Relay 803 operates, and a locking circuit is closed for relay 805 from battery through the upper winding and contact thereof, over back contacts of preceding similar relays, winding of relay 802 to ground at the front contact of relay 803. Relay 802 operates in this circuit and relays 805 and 802 are locked in a new circuit leading through the right front contact of relay 802, lower contact of relay 805 to ground on conductor 809. Relay 803 releases after an interval. Upon the release of relay 803 the multi-contact relay 806 is operated in a circuit from battery, through the winding of relay 806, front contact of relay 805, left front contact of relay 802 to ground at the

back contact of relay 803. The relay 806 is individual to the marker shown and serves to connect the conductors from said marker to the grid wires of the frame connector 800.

The next operation to take place is the energization of the vertical magnet 209 controlling the vertical row of contacts 201 in the incoming selector switch 200 in which appears the trunk 100. The preparatory circuit for this purpose may be traced from grounded conductor 809, lower contact of relay 806, conductor 811, normal contact of relay 714, conductor 715, through the connector 500, conductor 513, thence through the sender and sender selector 400, conductor 424, winding of relay 111 to battery. The manner in which this circuit is completed from the marker through the sender connector and thence through the sender and sender selector switch is fully described in my Patent 1,517,331, granted December 2, 1924. The relay 111 operates the vertical magnet 209 in a circuit from battery through the winding of said magnet, conductor 221 to ground at the left contact of relay 111. The magnet 209 rotates the bar 207 and prepares the contacts in the vertical row 201. The multi-contact relay 801 individual to the incoming selector switch 200 is also operated in a circuit from battery through the winding of said relay, conductor 812 to ground at the right contact of relay 111. Relay 801 connects the grid wires of the frame connector 800 to the leads extending to the incoming switch 200.

The magnet 209 operates the relay 714 in a circuit from battery through the winding of said relay, conductor 717, through the frame connector 800 to ground at the contact of magnet 209. Relay 714 closes locking circuits for the magnet 209 and relay 801. These circuits may be traced from battery through the winding and contact of magnet 209 and in parallel from battery through the winding and contact of relay 801, thence through the connector 800, conductor 814, contacts of relay 714, conductor 811, contact of relay 806, conductor 818 to the grounded conductor 809.

The next step in the process is to associate the marker with the particular one of the several final translators which has control over the group of final switches reaching the group of 500 lines containing the called line 319. The selection of the proper final translator is determined by the hundreds register 601. Therefore, when the relay 805 operates a circuit is closed for operating the relay 908 which is individual to this particular marker at the connecting device 900. The circuit for this purpose may be traced from ground through the back contact of relay 803, left front contact of relay 802, uppermost contact of relay 805, conductor 810, inner upper contact of relay 641,

right back contact of relay 611, outer right front contact of relay 610, inner contact of relay 625, conductor 628, winding of relay 908 to battery. Relay 908 operates relay 905 in a circuit through the left winding of the latter relay, front contact of relay 908, right contact of relay 906 to ground at the back contact of slow-to-release relay 907. Relay 905 operates relay 907 in a circuit from battery through the winding of the latter relay, left contact of relay 906, left contact of relay 905, conductor 910, right back contact of relay 711 to the grounded conductor 716. Relay 905 being slightly slow to release, does not retract its armatures while relay 907 is operating. Relay 907 operates and a circuit is closed from battery through the right winding and contact of relay 905, winding of relay 906, to ground at the contact of relay 907. Relay 905 locks and relay 906 operates in this circuit, thereby releasing relay 907. Relay 907, in releasing, operates the multi-contact relay 903 in the following circuit: battery through the winding of relay 903, right front contacts of relays 905 and 906 to ground at the back contact of relay 907. Relay 903 operates its contacts and extends the leads from the marker through to the translator shown in Fig. 10.

The operation of the final translator will next be discussed. Since the hundreds digit is such that the relay 613 of the register 601 is operated, a circuit is completed for operating the multicontact relay 1008 of the translator 1000. This circuit may be traced from battery through the winding of said relay, outer right contact of relay 1018, through the connector 900, conductor 911, inner right back contact of relay 612, right front contact of relay 613, right back contact of relay 614 to ground over conductor 626 as previously traced. Inasmuch as the units digit is such that only relay 620 of the register 603 is operated, a circuit is completed for operating the relay 1017. This circuit may be traced from ground through the right back contact of relay 623, conductor 630, connector 900, through the winding of relay 1017 and returning through the connector 900, conductor 912, outer right back contact of relay 615 to ground over conductor 626.

Since the tens digit is such that both relays 616 and 617 are operated a circuit is completed as follows for operating the vertical magnet 316 on the connector switch 300 which relates to the row of contacts 303 in which appears the called line 319: From ground over conductor 626, through the inner back contacts of relays 619 and 618, inner right front contacts of relays 617 and 616, conductor 631, connector 900, conductor 913, contact of relays 1017 and 1008, conductor 1019, winding of magnet 316, wind-

ing of relay 328 to battery. Magnet 316 rotates the bar 320 and prepares the contacts in the vertical row 303.

Magnet 316 operates the relay 1004 which is individual to the final connector frame 300 and which serves to connect certain leads in the translator to said frame. The circuit for this purpose may be traced from battery through the winding of relay 1004, back contact of relay 1025, conductor 1026, inner contact of magnet 316 to ground over conductor 1019 as previously traced. Magnet 316 and relay 1004 lock in circuits from battery through the winding and inner contact of magnet 316, thence through the lower contact of said magnet and in parallel thereto from battery through the winding of relay 1004 and thence over conductor 1026, through the lower contact of magnet 316, and thence over conductor 321, conductor 708, right back contact of relay 707, outer right back contact of relay 706, outer right back contact of relay 710, right back contact of relay 711 to the grounded conductor 716.

Inasmuch as the units digit determines the appearance of the wanted line in the section 311 of the switch 300, it will be necessary to operate the multi-contact relay 1006. The circuit for this purpose may be traced from battery through the winding of said relay, through the connector 900, conductor 914, inner right back contact of relay 621, right front contact of relay 620 to the grounded conductor 626.

The connection of the marker to the group of trunks interconnecting the incoming and connector switches will now be described. Since there are a number of groups of trunks leading from the incoming switches to the final switches, it is essential that the marker be connected to the particular group which leads to the final selector 300 containing the called subscriber's line. The identity of the group of trunks may be had from the incoming frame connector 800 and the identity of the group of final switches may be had from the translator 900. Accordingly, the multicontact relay 815 is operated in a circuit from battery through its winding, back contact of relay 816, conductor 819, through the connector 900, conductor 916, through the frame connector 800 and returning over conductor 708 to ground. Relay 815 is individual to the group of trunks including the trunk 213 and serves to connect the marker testing equipment to the sleeve conductors of these trunks. Relay 815 operates the relay 919 in a circuit from battery through the winding of the latter relay, thence through the connector 900 to ground at the contact of relay 815.

The next step is to test the trunks and links and also the called subscriber's line. The marker is provided with a series of testing relays 720 comprising a sufficient num-

ber of these relays for testing the horizontal links of the incoming selectors, the trunks outgoing therefrom and the horizontal links of the final selectors. The double wound 5 relays 721, 722, 723, etc., each have a winding for testing the horizontal link in the incoming switch and a winding for testing the trunk which has access to such link. Either winding is sufficient to operate the 10 relay and both windings will also operate the relay. The relays 724, 725, etc. pertain to the corresponding horizontal links in the connector switch. Assume, first that the link 205 of the incoming switch 200, the first 15 trunk 213 and the link 305 of the connector switch are all simultaneously busy. A circuit is, therefore, completed from battery through the left winding of test relay 721, innermost back contact of relay 727, through 20 the connector 800, conductor 1020 to the grounded sleeve conductor of the link 205. Another circuit is closed from battery through the right winding of relay 721, next 25 to the inner back contact of relay 727, inner right back contact of relay 728, conductor 729, through the connector 900, conductor 922, contact of the relay 815, conductor 822 to the grounded sleeve conductor of trunk 213. The link 305 also being busy a circuit 30 is closed for operating relay 724 which may be traced from battery through the outer left contact of relay 730, winding of relay 724, contacts of relay 919, conductor 923, connector 900, conductor 918, contact of relay 1006, through the connector 1002, conductor 1029 to the grounded sleeve conductor of the busy link 305. Had the link 205 and 35 the trunk 213 been idle the busy condition of link 305 would cause the operation of relay 724, which in turn, would cause the operation 40 of relay 721. The operating circuit for relay 721 in this case may be traced through its right winding, inner contact of relay 724, outer right back contact of relay 730, conductor 732 to ground at the inner right contact of relay 700. The relay 721, in operating, extends the start conductor 733 on to 45 the next test relay 722 which may or may not be energized according to the condition 50 of the corresponding links and trunk.

If, however, the first link 205, trunk 213 and the link 305 are all idle at the same time, the test relay 721 remains deenergized. The magnet 212 which controls the 55 vertical row of contacts 204, in which appear the trunks of the selected group, is also operated at this time. The circuit for this purpose may be traced from battery through the winding of said magnet, conductor 215, through the connector 800, conductor 824, through the connector 900, conductor 924, contacts of relay 815, conductor 820, contacts of relay 1006, contacts of relay 1004, conductor 1021, connector 900, contact of relay 919, conductor 708 to ground.

The magnet 212 rotates the bar 216 and prepares the contacts in the vertical row 204.

The magnet 212 operates the relay 730 in a circuit traceable from battery through the winding of said relay, contact of relay 703, conductor 734, through the connector 800, conductor 222, contact of magnet 212 and returning over conductor 223, through the connector 800 to ground over conductor 809. Relay 730 operates the relays 727, 728 75 and 705. The circuit for this purpose may be traced from the grounded conductor 732, right outer front contact of relay 730, thence in parallel through the winding of relay 727 and through the inner right contact of relay 710, conductor 743, back contact of relay 735, back contact of relay 721, winding of relay 728, winding of relay 705 to battery.

During the foregoing operations a test 85 is also made to ascertain the condition of the called subscriber's line. At the time the connecting devices 1001 and 1002 are operated, the magnet 310 is energized in a circuit from battery through its winding, thence through contacts of connecting devices 1002 and 1001 to the grounded conductor 708. Magnet 310 operates the common test link 307 which makes connection with the sleeve conductor of the called line 95 319. When relay 730 later operates a test circuit is closed from battery through the winding of relay 711, front contact of relay 730, middle right back contact of relay 710, left contact of relay 736, conductor 737, connector 900, conductor 1032, connector 1002, conductor 322, over the test links 307 100 to the sleeve conductor of the line 319. Assuming the line 319 to be idle at the time, relay 711 fails to operate.

With the test relay 728 operated as above explained a circuit is closed for operating the vertical magnet 318 on the final selector switch in the contacts of which the trunk 213 appears. This circuit may be traced 110 from the grounded conductor 708, thence through the outer right contact of relay 728, conductor 739, contact of relay 919, connector 900, conductor 920, through the contacts of the relay 815, connector 1002, winding of magnet 318 to battery. Magnet 318 rotates the bar 313 and prepares the contacts in the vertical row 301. The magnet 318 also causes the operation of the horizontal magnets 217 and 309. The circuit for magnet 217 may be traced from battery through the right winding of said magnet, conductor 218, contact of relay 801, contact of relay 806, conductor 826, outer left contact of relay 728, conductor 740, connector 900, conductor 932, connector 1002, contact of magnet 318, conductor 1026, contact of magnet 316 to the grounded conductor 321. Magnet 217 operates the bar 220 and establishes connection between 115 120 125 130

the trunk 100 and the trunk 213 through the medium of link 205.

The circuit for magnet 309 may be traced from battery through the right winding thereof, conductor 323, through the connectors 1002 and 1001, thence through the connector 900, conductor 934, contacts of relay 919, conductor 937, outer left contact of relay 728 and thence to ground over conductor 740 as above traced. Magnet 309 rotates the bar 334 and the trunk 213 is connected to the line 319 through the medium of the idle link 305.

When magnet 217 operates it operates relay 103 in a circuit from battery through the winding of said relay, sleeve conductor of the trunk 100, through contacts of the switch 200, left winding of magnet 217 to ground over conductor 218. Relay 103 locks through its lower contact to ground at the contact of relay 104. A holding circuit is now closed for the magnet 217 as follows: battery through both windings of magnet 217, thence through contacts of the switch 200 and through the lower contact of relay 108 to ground at the contact of relay 104. Relay 324 is now operated in a circuit from battery through its normal contacts and right winding, sleeve conductor 340, thence through contacts of the switch 200 to the grounded sleeve conductor of trunk 100. Relay 324 operates and a locking circuit is completed from battery through the winding of slow release relay 325, contact and winding of relay 324 to ground over the sleeve conductor 340.

The horizontal magnet 309 on the final switch 300 is held in a circuit from battery through both its windings, contacts of the switch, sleeve conductor 341 of the trunk 213 to ground at the outer right contact of relay 325.

The connection has thus been completed to the called line 319 and the apparatus is now ready to apply ringing current to signal the wanted subscriber. Before this is done, however, and while the marker is still associated with the switches, a test is made to determine whether or not the talking circuit which leads through contacts of the switch 200 and the switch 300 is in a continuous condition or whether there are any open points therein due to an improper operation of the switch contacts. For this purpose a test relay 731 is provided in the marker which is included in the test circuit and also in series with the source of talking battery at the right-hand side of the repeating coil 106, which relay operates provided the talking circuit is continuous to inform the marker that it may release and also cause the release of the sender to permit the application of ringing current. The test circuit may be traced from battery through the lower right winding of the re-

peating coil 106, winding of relay 105, lower back contact of relay 107, lower front contact of relay 108, thence over the ring side of the trunk, through the switch 200, over the ring of the trunk 213, through contacts 70 of the switch 300 to the ring conductor 342 of the line 319, thence through contacts of the switch 300 to conductor 344 of the test link 307, conductor 346, connector 1002, conductor 1030, connector 900, conductor 930, 75 winding of relay 731, conductor 931, connector 900, conductor 1031, connector 1002, conductor 347, conductor 345 of test link 307, through contacts of the switch 300 to the tip conductor 343 of line 319, contacts 80 of the switch 300, through the tip conductor of trunk 213, thence through contacts of the switch 200 to the tip conductor of trunk 100, upper contact of relay 108, upper back contact of relay 107, upper right winding of repeating coil 106 to ground. Assuming that the test circuit is continuous, the relay 731 operates and operates the release relay 407 in the sender to cause the restoration of said sender. The circuit for relay 85 407 may be traced from battery through the winding thereof, conductor 425, connector 500, conductor 514, outer left contact of relay 731, conductor 737, through the connector 900, conductor 1032, connector device 1002, conductor 322, through contacts of the test link 307 to the sleeve conductor of the line 319, thence through contacts of the switch 300 including horizontal link 305 to the sleeve conductor 341 of the trunk 213 100 to ground at the outer right contact of relay 325. Relay 407 operates and locks to ground at the contact of relay 411 which latter relay may be operated during the setting of the registers. Relay 407 at its outer right front contact operates the release relay 406 which releases relay 410, which in turn, releases relay 411. These relays remove the holding ground potential from the various conductors whereupon the sender and sender selector switch 400 are restored to normal. When relay 407 operated it opened the circuit of relay 501, which in turn, released to cause the release of relays 502, 503, 506, 508, 507 and 504. Thus, the 105 sender is disconnected from the marker. 110

The relay 731, in operating, also operates the marker release relay 703 in a circuit from battery through the winding of this latter relay, inner left contact of relay 731 120 to ground over conductor 737 as previously traced. Relay 703 which is slow to release operates and opens the holding circuits of relays 730 and 700 and these latter relays release, in turn removing ground from the various holding conductors to permit the restoration of the marker and the associated equipment.

With the release of the marker the vertical magnets 209, 212, 315 and 316 are re- 125

stored and the associated bars return to normal and the connection through the switches is held by the maintained energization of the horizontal magnets 217 and 309.

5 The common marker and controlling equipment including the translator has now been restored and may be taken in connection with other calls and the equipment is now ready to apply ringing current to the 10 called subscriber's line.

At the time the sender releases the circuit of relay 101 is opened and this relay again deenergizes. Relay 101 closes an operating circuit for the relay 107 which 15 may be traced from battery through the outer left contact of relay 109, winding of relay 107, contact of relay 110, inner upper front contact of relay 108, inner upper contact of relay 101, contact of relay 103 to 20 ground. It will be noted that relay 103 reoperates in series with the trunk 100 as soon as relay 101 closes its back contacts. Relay 107 operates and ringing current is applied over the following circuit: from 25 the ringing source 112, winding of ringing cut-off relay 110, through the lower front contacts of relays 107 and 108, thence over the ring side of the subscriber's line and returning through the upper front contacts 30 of relays 108 and 107 to ground. When the called subscriber answers the ringing cut-off relay 110 operates and removing the previously existing shunt permits the relay 109 to operate in the following circuit: battery, through the outer left contact of relay 109, winding of relay 107, contact and right winding of relay 109, inner upper contact of relay 108, thence to ground at the contact of relay 103 as traced. Relay 109 35 operates and locks and in so doing opens the circuit of relay 107 which becomes deenergized and the trunk circuit is completed through to the right windings of the repeating coil 106.

40 It will be noted that the circuit of relay 104 is opened when relay 101 releases following the release of the sender. Relay 104 does not become deenergized to remove ground from the holding conductor, since 45 a new holding circuit is immediately supplied therefor and may be traced as follows: battery, through the winding of relay 104, inner lower back contact of relay 101, left normal contact of relay 109, inner upper 50 front contact of relay 108, inner upper back contact of relay 101 to ground at the contact of relay 103. When the called subscriber answers and relay 109 operates, the holding circuit for relay 104 is then completed directly to ground at the left front 55 contact of relay 109. When the called party answers the called supervisory relay 105 is operated in the usual manner.

60 At the end of conversation the parties 65 restore their receivers and relay 103, con-

sequently, becomes released, in turn, releasing relay 109 and relay 104. Relay 104 releases the relay 108 and removes ground from the sleeve conductor of trunk 100 whereupon the horizontal magnet 217 de- 70 energizes and releases the switch 200.

The removal of ground potential from the trunk 100 also results in the removal of ground from the conductor 340, whereupon relays 324 and 325 become deenergized. 75 Relay 325 opens the holding circuit of horizontal magnet 309 which deenergizes and releases the connector switch 300.

It will now be assumed that the talking circuit extending through the switches is not continuous at the time the test is made. Therefore, the test relay 731 fails to operate, since relay 731 does not operate neither the sender nor the marker releases at this time. In order that the marker may not be held up indefinitely, a time measuring device 744 is provided to count a definite interval of time within which the marker is allowed to complete its functions. When the marker is first taken for use the relay 745 is operated upon the next closure of the upper contact of the device 744. This circuit may be traced from battery through the winding of relay 745, normal contact thereof, upper contact of interrupter 744 to ground at the contact of relay 700. Relay 745 locks to the grounded conductor 713. Upon the next closure of the lower contact of the interrupter 734, a circuit is completed for operating the slow release relay 704 and may be traced from battery through the winding of said relay, right contact of relay 745, outer right contact of relay 700, lower contact of device 744, to the grounded conductor 713. Relay 704 operates the relay 408 in the sender in a circuit from battery through the winding of relay 408, conductor 426, connector 500, outer right back contact of relay 731 to ground at the inner left front contact of relay 704. Relay 408 locks to the grounded contact of relay 411 and removes ground from conductor 418 to cause the release of the sender connector 500. Relay 408 also lights the trouble lamp 427 whereby the monitoring operator is notified of the existence of the trouble condition. After having disposed of the trouble the operator may release the sender by operating the key 428 causing the holding relays 411 and 410 to become deenergized. 110

115 When relay 704 operates it opens the holding circuit of relay 700 and the latter relay releases. Relay 704 locks through its inner right contact, trouble key 742 to ground at the outer left contact of said relay. Relay 704 at its left front contact also supplies a substitute holding ground to the conductor 713 to prevent the release of the marker. The trouble operator may after the 120 source of the trouble has been located, re- 125

store the marker by operating the key 742.

In case the talking circuit is continuous at the time the test is made but no ground is connected to the left-hand armatures of relay 731 due to the open condition of the conductor 737 which leads to the test conductors of the switch, relay 408 in the sender does not operate, but relay 405 operates instead after the time measure has counted the interval. The circuit for relay 405 may be traced from battery through the winding thereof, conductor 430, connector 500, right front contact of relay 731 to ground at the inner left front contact of relay 704. Relay 405 locks to ground at the contact of holding relay 411 and closes a circuit for the trouble lamp 431. Lamp 431 illuminates, notifying the trouble operator of the nature of the existing trouble.

20 In case the called line is busy at the time the test is made, the busy test relay 711 is operated in the circuit hereinbefore traced. Relay 711 at its right contact causes the release of the operated test relays 720, the 25 marker connector 900, relay 815, the relay 910, connector 1002, the line vertical magnet 316, test horizontal magnet 310 and the vertical magnet 212. The connection originally started is thus wiped out when the 30 called subscriber's line is found busy.

When the magnet 212 releases it causes the release of relay 730, which in turn, releases relay 727. Relay 727 again connects the test relays 720 to the test conductors 35 leading to the incoming frame 200 for the purpose of determining an idle horizontal link to connect the tone apparatus to the incoming trunk. Relay 711 closes a circuit for relay 706 which may be traced from battery, through the winding of the latter relay, inner left contact of relay 711, outer right contact of relay 730 to ground at the inner right contact of relay 700. Relay 706 locks to the conductor 713. Relay 706 operates the magnet 210 of the incoming selector 40 by means of a circuit from battery through the winding of said magnet, thence through the connector 800, left front contact of relay 711, inner right contact of relay 706 to the 45 grounded conductor 713. The magnet 210 prepares the contacts in the row 202 which is reserved for the purpose of connecting a tone coil 230 to the incoming trunks. Magnet 210, in operating, operates the relay 730 in a manner similar to that discussed in connection with the magnet 212. Relay 730 operates the relay 728 in a manner described provided the horizontal link 205 is idle. Relay 728 closes a circuit for operating the horizontal magnet 217 as described hereinbefore. As soon as the time measuring relays 725 and 753 function, the marker 50 is released. When relay 705 operates in series with relay 728, a circuit is closed from

battery through the winding of slow release 65 relay 753, back contact of relay 752, left contact of relay 705 contact of relay 706 to ground over conductor 713. Relay 753 closes an obvious circuit for relay 752 which operates and locks to conductor 713. Relay 70 752 opens the circuit of relay 753 which releases after an interval and operates the relay 703 as follows: Battery, through the winding of relay 703, inner contact of relay 753, left front contact of relay 752, left contact of relay 705, inner right contact of relay 706 to the grounded conductor 713. Relay 703 causes the release of the marker in the manner hereinbefore described. The tone apparatus is now connected to the 80 trunk 100 and a busy tone is produced for the purpose of notifying the calling subscriber that the called subscriber's line is busy.

What is claimed is:

1. In a telephone system, a subscriber's line, a selective switch having contacts, means for operating the contacts of said switch to extend a talking connection to said line, a test circuit separate from the loop 90 of the subscriber's line and including the contacts of said switch for testing the condition of the connection extended to said line, and means operated when a connection is extended to said line for rendering effective 95 the test circuit.

2. In a telephone system, a subscriber's line, a plurality of selective switches, means for operating said switches to extend a talking connection to said line, a test circuit 100 separate from the loop of the subscriber's line and including the talking conductors of the connection extended through said switches to the subscriber's line for testing the condition of said connection, and means 105 operated when a connection is extended to the line for rendering said test circuit effective.

3. In a telephone system, a subscriber's line, a selective switch having contacts, means for operating the contacts of said switch to extend a talking connection to said line, a test circuit separate from the loop of the subscriber's line for testing the continuity of the connection extended through 115 said switch and means to prevent placing the connection in condition for conversation if the test reveals that said connection is not continuous.

4. In a telephone system, a subscriber's line, a selective switch, means for operating the selective switch to extend a talking connection to said line, a source of signaling current arranged to be applied to the subscriber's line, a test circuit separate from the loop of the subscriber's line and including the contacts of said switch for testing the condition of the connection extended 120 125

thereto, and means controlled by said testing circuit to prevent the application of said source of signaling current.

5. In a telephone system, a subscriber's line, a trunk circuit having a source of talking current therein, a selective switch for extending said trunk to the subscriber's line, means for operating said switch, a test circuit including said source of current for testing the connection extended through the switch to said line, and means operated upon the operation of said switch for rendering effective said test circuit.

6. In a telephone system, a subscriber's line, a trunk circuit having a source of talking current therein, a source of ringing current arranged to be applied to the subscriber's line, a selective switch for extending said trunk to the subscriber's line, a marker for controlling the selective operation of said switch, a test circuit including said source of talking current for testing the connection extended through the switch to the subscriber's line, and means in said marker controlled by the test circuit to withhold the application of said source of ringing current.

7. In a telephone system, a subscriber's line, a trunk circuit having a source of current therein, a selective switch for extending said trunk to the subscriber's line, a marker for controlling the operation of said switch, means for releasing said marker after the operation of said switch, a test circuit including said source of current for testing the connection extended through the switch to said line, and means controlled by said

test circuit to prevent the release of said marker.

8. In a telephone system, a subscriber's line, an automatic switch, means for operating said switch to extend a talking connection to said line, a test circuit separate from the loop of the subscriber's line and including the contacts of said switch for testing the continuity of the connection extended to said line, a signal, and means controlled by said test circuit for operating said signal if the extended connection is not continuous.

9. In a telephone system, a subscriber's line, a trunk circuit having a source of current therein, a selective switch for extending said trunk to the subscriber's line, a marker for controlling the operation of said switch, means to release said marker after the operation of the switch, a test circuit including said source of current for testing the connection extended through the switch to the subscriber's line, a signal, and means controlled by said test circuit to prevent the release of the marker and to render said signal effective.

10. In a telephone system, a subscriber's line, a selective switch having a plurality of links for extending a talking connection to said line, a test link common to said first mentioned links, and a test circuit completed through said test link for testing the condition of the connection extended to said line before said connection is placed in condition for conversation.

In witness whereof, I hereunto subscribe my name this 17th day of April A. D., 1924.

SAMUEL B. WILLIAMS.
